THOMAS PROSSER, OF NEW YORK, N. Y.

Letters Patent No. 65,942, dated June 18, 1867.

IMPROVEMENT IN MACHINES FOR GRINDING AND POLISHING.

The Schedule referred to in these Letters Patent and making part of the same.

TO ALL WHOM IT MAY CONCERN:

Be it known that I, THOMAS PROSSER, of the city, county, and State of New York, have invented a certain new and useful Improvement in Grinding and Polishing Machines, of which the following is a full, clear, and exact description; reference being had to the accompanying drawings, forming part of this specification, and in which—

Figure 1 represents a plan of a grinding machine constructed according to my invention.

Figure 2, a longitudinal vertical section thereof through the line $x x$ in fig. 1.

Figure 3, a front or end elevation of the same; and

Figure 4, a vertical section taken as denoted by the line $z z$ in fig. 1.

Like letters indicate like parts throughout the several figures.

The nature of my invention consists, firstly, in a novel combination of a revolving grinding-wheel and carriage or vise for holding the work to be ground, the latter having, in addition to a reciprocating motion across the periphery of the grinder, and in addition to the feed, an adjustability on the bed that carries it, to give it a parallel or angular set relatively to the axis of the grinder; and, further, consists in a like combination in which the carriage is provided with a revolving mandrel that serves to rotate the work; and of a similar combination made to automatically establish the feed of the work to the grinder, or latter to the former; likewise, in a novel combination, with a reciprocating carriage, of an adjustable friction-wheel contrivance and feed-connecting devices, to facilitate change of the feed from an automatic to a hand one; and in a peculiar double-wheel pawl escapement feeding motion set in action by the reciprocating carriage.

For the information of others whom it may concern, I proceed to describe my invention with reference to the accompanying drawings, in which—

A represents the grinder or polisher, that may be of any proper material or suitably coated on its periphery according to the grinding or polishing work it is required to perform, and other circumstances, but which it will suffice here to describe as a grinding-wheel of any desired diameter and width of its face, mounted on a horizontal shaft, B, and arranged as, say, for grinding cylindrical or conical bodies. C is a pulley on the shaft B, for giving the necessary revolving motion by belt from a prime or other mover to the grinding-wheel A, the shaft of which works in bearings on a frame, D. At the one end of this frame is a bed-plate, E, arranged, in the present instance, to work or be adjusted by V-slides, towards and from the grinding edge of the wheel A, and having mounted on it a cross sliding upper plate or bed, F, travelling parallel with the axis of the wheel A. This upper plate F has arranged on it the vise which holds the work to be operated on. For grinding arbors, spindles, and other cylindrical, also conical, bodies, this vise may consist of a carriage frame, G, extending lengthwise of the upper plate F, and secured thereon by screw-bolts b, fitting through curvilinear slots c, in projections at the ends of said frame G, to admit of the latter being adjusted on the face of the sliding-plate F, so as to present the work to the wheel A at different angles or rather different positions relatively to the periphery thereof, accordingly as the work is cylindrical or conical. This will be readily understood. Supposing the spindle or other work, to be held by centres d d at opposite ends of the frame G, and the latter, with its work, to be reciprocated in a direction parallel with the axis of the wheel A, by the travel of the upper plate F, then by merely adjusting the frame G through the slots c and bolts b, on the plate F, so that the centres d d hold the work in such position relatively to the grinding-wheel as that its line of travel next to and across the periphery of the wheel A will always be parallel with the axis of the latter, then it is immaterial whether the work be cylindrical or conical, the grinding course stands the same. The one centre d is connected with a live spindle or head-stock mandrel, H, which is made hollow, and, working in bearings e, at one end of the frame G, is rotated by belt passing round a pulley, f, in the same direction as the grinding-wheel, so that the peripheries of said wheel and work pass each other in opposite directions, the work being made to turn with the mandrel by gearing it thereto through a clutch or dogs, as in lathe-work, or in any other suitable manner, or said mandrel may be furnished with a face-plate. The opposite or back centre d forms part of an ordinary lathe-puppet, which may be adjustable or not on the frame G that forms the carriage, separately considered, or in connection with the cross sliding-bed F, while the head-stock mandrel and puppet at opposite ends of the frame G constitute, in connection with the latter, the vise proper, which, however, may be otherwise constructed according to

the character of the work it is required to hold or description of work to be done. To feed the work up to the wheel A, a shaft, I, may be employed, having on its inner end a screw-thread, which works through a box, g, attached to the bed-plate E, and which has at its outer end a hand-wheel, h, but this, instead of a hand-feed, may be made automatic, as hereinafter described, or either may be used at option of the operative.

The work to be ground it is proposed, according to the arrangement shown in the drawings, to reciprocate across the periphery of the grinding-wheel, as already referred to. This may be done by the following means, though others may be used, which remark applies also to the details connected with the feed of the work up to the wheel. Attached to the frame D are brackets i, which serve to carry a shaft, j, that is provided with an endless screw, k; and which may be driven by belt passed round any one of a series of pulleys, k¹ k² k³, according to the speed required, said endless screw gearing with and serving to drive a worm-wheel, l, that is mounted on a hollow shaft, m, having its bearing in a sleeve, n, that projects from the frame D. This hollow shaft m has arranged within it a shaft, J, that is made to rotate with the hollow shaft m, but at liberty to slide lengthwise therein by means of a feather and groove connection of said shafts. On the inner end of the shaft J is secured a crank, K, which may have a variable throw by providing it with a series of holes at different distances from its centre on the same or opposite sides thereof, through any one of which holes the pin is passed that connects a pitman, L, with the upper bed-plate F by a bracket, o. By this means, it will be seen, the carriage holding the work is reciprocated to and fro across the periphery of the wheel A, the reciprocating stroke being governed by the throw of the crank, according to the length of the piece to be ground, while, by the sliding connection of the shaft J with the hollow shaft m, such reciprocation in no ways interferes with the feed of the work up to the wheel by the shaft I, nor yet the latter action with the former.

As it is desirable in many instances to make the feed of the work up to the grinding-wheel automatic, that is, to give a fresh feed each single reciprocating action, or travel in each direction of the carriage or vise, this I propose to do as follows, though other means or details may be substituted: The hand feed-wheel h is formed with a wedge-shaped periphery, which fits into a V-grooved wheel or disk, p, made fast to a shaft, q, that works in suitable bearings, and may be set by means of a binding-screw, r, to throw more or less friction of the wheel p on the hand-wheel h, so as to cause the former to drive the latter and its screw-shaft I. On the inner end of the shaft q is a spur-wheel, s, that meshes into a corresponding wheel, s', hung on an independent shaft carried by an arm of the bracket t, which is attached to the bed-plate E. On the upper bed or plate F, at a suitable distance apart from each other, and which distance may be varied by making them adjustable, so as to regulate the amount of feed each time and to adapt them to any alteration in the reciprocating stroke of the carriage, are pivoted dogs or pawls u u', which serve alternately, as the plate F reaches the termination of its reciprocating stroke, to act first the one dog u against the wheel s, and then, on the return of said plate, the other dog u' against the wheel s', which, by setting the wheels in motion, gives the necessary amount of turn to the shaft q to set in motion the wheels p and h, and so work the screw-shaft I, that is, the more immediate means of establishing the feed. This arrangement may be denominated a double-wheel pawl escapement. Here it may be observed that there is not only a smoothness of action by using friction-gear or wheels p h, but by simply slackening or tightening up the binding-screw r, the feed may be instantly changed from an automatic to a hand one, and *vice versa*. In some cases the feed motion, automatically produced by the reciprocating motion of the carriage or its bed-plate, may be applied directly to the carriage or to the grinding-wheel itself, as may be desirable, in grinding tires for locomotives or other large circular work.

For internal grinding, as in boring, the grinding-wheel may work "over neck," said wheel being of size to work within the article to be ground. The position of the grinding-wheel may, in fact, be considerably varied. For instance, by having its axis parallel with the reciprocating action of the vise or carriage, it is capable not only of doing lathe-work, but, to a limited extent, planing also, though the latter may be more perfectly or fully accomplished by arranging said wheel's axis at right angles to the reciprocating vise or carriage and over the latter; or it may be in line with the bed-plate of the carriage for boring cylinders and cones, also for externally turning the same, in which case the spindle or mandrel should run over the bed-plate and carry a face-plate, as in lathe-work, said face-plate and grinding-wheel both working "over neck."

What I claim herein as new and useful, and desire to secure by Letters Patent, is—

1. The combination of the wheels s s', pawls u u', friction-wheels p h, and screw I with the reciprocating carriage for establishing an automatic feed motion, substantially as specified.
2. The reciprocating carriage F, with its frame or vise G, made adjustable thereon, parallel or angularly to the axis of the grinding-wheel, in the manner described.
3. The friction gear-wheels h p, made adjustable as regards their binding action, one upon the other, substantially as and for the purpose set forth.

THOS. PROSSER.
